Machinery Corporation, Paterson, N. J., a cor-
poration of New Jersey

Application October 23, 1934, Serial No. 749,594
In Great Britain November 28, 1933

26 Claims. (Cl. 192—148)

This invention is concerned with improvements in or relating to driving and stopping mechanisms and is hereinafter illustratively described as concerned with machines which are arranged 5 to sew together parts (such for example as the end, side and bottom portions) of a suit case, attaché case or the like which extend at right angles to each other.

When a high speed machine is used for sewing 10 together the parts of a case or the like, pronounced difficulties would become manifest if it were attempted to stop the machine suddenly by the use of a single revolution clutch of customary type since great strains would be thrown suddenly on to numerous parts of the machine and 15 excessive wear and possible breakage would be thereby entailed.

An object of the present invention is to provide, for use in a high speed machine, a particularly efficient and novel form of stop motion 20 for bringing the machine to rest from its high speed within a very short time without throwing excessive strain on parts of the machine.

As will be appreciated greater care is necessary 25 on the operator's part in controlling the work during the putting in of individual stitches around an end corner of a case than is necessary during the sewing of a seam along a straight edge of the work, and greater care is also necessary 30 in controlling the work when workpieces of small or awkward shapes (such for example as parts of saddle-bags for cycles or parts of cases for musical instruments) are being sewn together than when relatively large pieces of simple 35 shape are being sewn together.

Accordingly, another object of the present invention is to provide, in a high-speed machine, a novel form of variable-speed driving mechanism by which the machine may be driven at a high 40 speed when the nature of the work being operated on will allow of it and by which it may be driven at a reduced speed when the nature of the work calls for greater care on the part of the operator.

The machine hereinafter described is provided 45 with a two-speed driving mechanism, controlled by the operator, by which the machine may be caused to run at a relatively high speed when desired and by which it may be caused to run at a considerably lower speed when desired. A stop motion is provided, which may be controlled by the operator to allow the machine to sew a seam of stitches in a continuous manner before the machine is brought to rest and may also be controlled 50 to cause the machine to come to rest after

sewing but a single stitch when the operator so desires, which stop motion, when rendered operative, applies a braking effort to the machine to bring it to rest and a dashpot is provided for automatically causing the braking effort to operate over a longer period when bringing the machine to rest from high speed than when bringing the machine to rest from low speed. Such an arrangement allows progressively decreasing 5 braking effort to be applied to the moving parts 10 of machine so that they are brought to rest with great smoothness thus avoiding straining the parts and obviating shock on the stopping of the machine.

The various objects and the several features of 15 the present invention (which latter are set out in the appended claims) will be fully understood from a consideration of the following description with reference to the accompanying drawings.

In the drawings:—

Figure 1 is a left hand side elevation of the machine of the illustrative embodiment.

Figure 2 is a left hand side elevation, partly in section and to a larger scale of the lower portion 25 of the head.

Figure 3 is a front elevation, also partly in section and to the same scale as Figure 2, of the left portion of the machine head.

Figure 4 is an isometric view, on an enlarged scale (from the right hand side) illustrating how 30 certain trip levers cooperate with certain latches of the machine.

Figure 5 is a view similar to Figure 4 but looking from the opposite side.

Figure 6 is an isometric view, from below and 35 from the right, showing details of a pawl associated with the two-speed driving mechanism, and

Figure 7 is a left hand side elevation, partly 40 in section, showing certain parts of a two-speed driving mechanism for the machine.

The machine of the said illustrative embodiment comprises a column 1 on the upper end of which a head casting 3 which supports the sewing and other instrumentalities together with 45 their actuating mechanisms, is mounted. Near the lower end of the column and on its left hand side is mounted a countershaft 5 which extends forwardly and rearwardly of the machine and has fast and loose pulleys 7 and 9 on its rear 50 end. The countershaft also has mounted on it, near its forward end, a two-speed driving device hereinafter described which is coupled by a belt 11 to a driving pulley 13 situated on the left hand end of a horizontal main shaft 15 of the machine 55.

which extends transversely of the machine (i. e. from left to right) in the machine head. A single treadle 17 is provided for causing a driven member 19 secured to the machine shaft 15 to engage 5 with the said driving pulley to set the machine in operation and for causing the two speed driving device to drive the pulley 13 at a high speed or a low speed at will.

The machine of the present illustrative embodiment is provided with an external work support 49 (which is similar in general appearance to that referred to as 28 in Patent No. 1,695,718), which work support has two relatively long work-supporting faces extending parallel to 10 the line of feed and arranged at right angles to each other to support two work-pieces (e. g. the bottom or a side and an end portion of a case) which are to be sewn together at right angles.

20 In order to maintain the two parts of the work to be sewn together in proper position on the external work support 49, a work-entering horn indicated at 53 is provided in the illustrative machine which horn is generally similar in appearance to that referred to as 1 in Patent No. 1,695,718, but which carries, in place of the work-engaging tablet 43 described in that specification, a pair of small freely rotatable frustoconical rolls 55, 57 (the rear sides, i. e. the work-engaging sides) of which are mutually perpendicular and are maintained in parallel relation to the mutually perpendicular work-engaging faces of the external work support 49.

The two-speed driving device aforementioned 35 on the countershaft 5 of the machine comprises a gear wheel 189 fast on the forward end portion of the shaft with which gear wheel mesh two pinions 191 (one only of which is shown in Figure 7) mounted on pins 193 projecting forwardly 40 from a pulley member 195 freely rotatable around the countershaft close to the rear side of the gear wheel, the said pins being arranged diametrically opposite each other on the pulley member. The two pinions 191 also mesh on their 45 outer sides with an internal gear 197 formed around the interior of the periphery of a drum 199 freely mounted on the forward end of the shaft which drum is arranged to be held stationary when the machine is to be driven at low 50 speed by a relatively fixed pawl 201 (Figures 1 and 6) engaging ratchet teeth 203 formed on an annulus secured to the drum 199 so that rotation of the countershaft will, through the rotation of the gear wheel 189, cause the pinions 191 to run 55 around the internal gear 197, and thus impart a rotation to the pulley member 195 which takes place in the same direction as the rotation of the countershaft. The relative dimensions of the gear wheel 189 pinions 191 and internal gear 197 are conveniently such that when the pulley member 60 is driven through the epicyclic train just described, it makes one revolution for every three revolutions of the countershaft.

The countershaft has rigidly secured to it just 65 rearward of the pulley member a disc 205 to which is secured on that side nearer the pulley member a leather friction ring 207 and the pulley member 195 is arranged to be slid rearwardly along the shaft into firm clutching engagement 70 with this disc when it is desired to drive the machine at high speed, the epicyclic gearing being then inoperative. For this purpose the clutch controlling treadle 17 of the machine is coupled to a quick-pitch plunger 209 arranged coaxially 75 with the countershaft the rear end of which

plunger bears against the end of a sleeve on the forward side of the drum 199. Depression of the said treadle to its lowest position causes a rearward movement of the said plunger which thereupon urges the drum 199 rearwardly along 5 the countershaft to press against the pulley member and thus move it also rearwardly, so that the pulley member becomes firmly clamped between the drum 199 and the disc 205, the pulley then being driven uniformly with the countershaft at 10 the same speed and in the same direction as the latter. When the pulley member becomes thus clamped against the said disc the epicyclic gearing before described rotates as a whole with the pulley member, countershaft and drum and 15 therefore is inoperative to drive the pulley member at its reduced speed.

The pawl 201 aforesaid which engages the ratchet teeth on the drum to hold the latter stationary while the pulley member is being driven 20 at its low speed is secured on a horizontal and freely rotatable pin 211 (Figure 6) and has a short arm 213 secured to it which carries a plug of leather 215 which contacts with the forward face of the drum 199. The pin 211 is mounted 25 in a fixed lug 217 and is urged rearwardly to press the leather plug 215 against the drum by a spring 219 encircling it and bearing against a shoulder on it.

The action of the epicyclic gearing, when the pulley member is being driven at its low speed, tends to cause the drum to rotate in a clockwise direction when viewed from the front, i. e. in a direction opposite to that in which the countershaft runs, and the friction between the leather 35 plug and the forward face of the drum swings the pawl into engagement with the teeth on the drum to prevent the drum rotating in this direction. When however the pulley member and therefore also the drum is directly driven from 40 the countershaft through the disc 205 the drum rotates in a counterclockwise direction and the friction between the leather plug and the drum causes the pawl to swing to a position in which it is out of engagement with the teeth on the 45 drum. A stop pin 221 secured to the arm 213 lies within a cut-away portion 223 of the lug 217 and by contact with the lower end thereof limits the swinging movement of the pawl away from the ratchet teeth.

The pulley member 195 is coupled by the belt 11 to the pulley 13 which is freely rotatable on the main shaft 15 of the machine by which latter pulley the machine is driven through a cooperating clutch member hereinafter described. Conveniently the two speed driving device is arranged to drive the machine at a high speed of 900 revolutions per minute and a low speed of 300 revolutions per minute.

For ensuring that the machine, whether it is 60 being run at its high speed or its low speed, will be brought to rest smoothly and evenly in a single revolution without imparting severe shock to the machine parts and to ensure that the various operating instrumentalities will occupy the 65 positions desired when the machine has come to rest, there is incorporated in the illustrative machine a stop motion of novel and ingenious character which will now be described.

The pulley 13 on the main shaft of the machine 70 is freely rotatable on the left hand end of the main shaft 15 and as shown in Figure 3 is dished inwardly from its right hand face to provide an internal clutching face 225. A cooperating clutch member 227, dished to correspond with the said 75

internal clutching face 225, is keyed to the shaft 15 to the right of the pulley and is arranged to be slid axially along the shaft towards the left into clutching engagement with the said pulley. The cooperating clutch member 227 is also arranged to be slid towards the right out of engagement with the pulley 13 and into engagement with a stationary braking face 229 surrounding the main shaft to bring the machine parts to rest. The cooperating clutch member 227 has a sleeve-like hub 231 extending to the right along the main shaft and a cam groove 233 is formed around said hub. A short forwardly and rearwardly extending rod 235 passes below the said hub at right angles to the main shaft and has pivoted on it two clutch trip levers 237, 239 which extend upwardly on the forward and rear sides of the said hub respectively and carry cam rolls 241 (see particularly Figures 4 and 5) which engage in the opposite sides of the cam groove 233 in the hub. The lower ends of these trip levers lie more or less side by side, considered forwardly and rearwardly of the machine, and the formation of the cam groove 233 is such that the lower ends of the trip levers move to and fro, in opposite directions to each other and at a substantially constant velocity when the machine is running at a constant speed, once in each machine cycle. The rod 235 has eccentric end portions which enter into fixed bearings so that by rotating the rod the positions of the lower ends of the trip levers towards the left or right of the machine can be adjusted. Four springs 243 housed within the hub of the cooperating clutch member tend to urge the latter along the shaft towards the left into clutching engagement with the pulley and a pair of latches 245, 247, one for each of said trip levers, is provided to engage with the lower ends of the trip levers at certain times and, by holding these lower ends against movement towards the right, to cause the cooperating clutch member to be moved out of engagement with the pulley and into engagement with the stationary braking face, through the action of the cam groove on the cam rolls at the upper end of the trip levers in a manner which will be clearly understood.

The latches 245, 247 comprise a pair of fingers pivoted side by side (considered forwardly and rearwardly of the machine) on a horizontal forwardly and rearwardly extending pin 249 which is carried by a depending arm 251 of a bell crank carrier lever which is mounted to rock about a fixed horizontal shaft 253 and has a laterally projecting arm 255 to which is connected means hereinafter described. The latches are normally urged upwardly by springs 257 (indicated only in Figure 3) secured to them until their left hand ends contact with the lower ends of the trip levers.

The rearward one 247 of the two latches has an upwardly extending shoulder 259 formed on it against which the right hand side of the lower end of the rearward trip lever 239 is arranged to strike in the manner hereinafter described when the machine is to be brought to rest when running at low speed (the forward latch and the forward trip lever playing no part in braking the machine when it is being brought to rest from low speed) and by which, since movement of the lower end of this trip lever towards the right is thus prevented, continued rotation of the main shaft causes, through the cam groove 233, the cooperating clutch member to be disengaged from the pulley and brought into firm contact

with the stationary braking face 229 to stop the machine. The forward one 245 of the two latches also has an upwardly extending shoulder 261 formed on it which shoulder is spaced further towards the right of the machine than the shoulder 259 on the rearward latch for a purpose hereinafter described and cooperates with the forward one 237 of the trip levers to assist the rearward latch and the rearward trip lever to bring the machine smoothly to rest in a single cycle when running at high speed in the manner hereinafter explained. To enable the machine to be started into operation at low speed the rearward latch 247 is arranged to be drawn downwardly out of engagement with the trip lever 239 and to enable the machine to be started into operation at high speed both latches are arranged to be drawn downwardly away from the lower ends of the trip levers to allow the cooperating clutch member to be moved by the springs 243 to engage the pulley on the main shaft by connections to the clutch treadle 17 the precise arrangement of the means for withdrawing the latches being hereinafter described.

It will be appreciated that if the latches were held in fixed position after the trip lever 237 has engaged the shoulder 261 on the forward latch 245 when the treadle has been released to bring the machine to rest from high speed the cooperating clutch member aforesaid would be likely to be thrust and held against the stationary braking face with great force and therefore great strain would be likely to be imposed on the machine parts since the action of the cam groove 233 would be to endeavour to bring the cooperating clutch member to rest almost immediately it engaged the braking face. If on the other hand the latches were able to move towards the right against but a light resistance under the action of the trip lever 237 as the latter engages the shoulder 261 on the latch 245 in stopping from high speed it would quite likely be found that the resistance offered by the latch 245 to movement of the trip lever 237 would be insufficient to bring the machine to rest smoothly in the manner desired.

In order to overcome these difficulties there is provided in the present illustrative embodiment an adjustable dashpot device which is so coupled to the latches as to offer such a firm yet yielding resistance to movement of the latches towards the right as the machine comes to rest from high speed that, immediately the trip lever 237 engages the latch 245, the cooperating clutch member will be moved out of clutching engagement with the pulley and into firm yet not excessive engagement with the stationary braking face, the said dashpot also acting to control the braking pressure between the cooperating clutch member and the stationary braking face in such a manner as to bring the parts of the machine smoothly to rest within the final cycle.

The said dashpot device comprises a main oil chamber 263 of substantially cylindrical shape which is enclosed on all sides and has a vertical valve 265 passing axially through it which seats on a valve seating 267 in the bottom of the oil chamber. An oil duct 269 runs from the bottom of the chamber 263 below the valve to the bottom of a vertical open topped cylinder 271 secured to the side of the oil chamber. A dumbbell plunger 273 is slidably mounted in this cylinder and makes a fairly tight fit in the cylinder. A rounded lower end of a rod 277 rests within a depression in the upper end of the plunger 273.

and this rod is connected at its upper end to the arm 255 of the bell crank lever to which the latches are pivoted.

This arrangement is such that when either of the trip levers 237, 239 engages the shoulder on one of the latches 245, 247 and therefore acts to move the latches toward the right, the pushing action of the trip lever on the latch will swing the arm 255 downwardly and thus cause the plunger 273 to be urged downwardly along the cylinder 271. Downward movement of the plunger is resisted by the presence of the oil beneath it which however is allowed to escape from below the lower head on the plunger (which alone of the two heads on the plunger is actually submerged in the oil) upwardly through the latter by means of an adjustable port 279, constituting a bleed valve, the effective opening of which can be varied by adjustment of a conical-ended stem 281 threaded into the plunger and projecting at its lower end into the port 279. As will be understood therefore the plunger 273 and the cylinder 271 constitute a dashpot device which offers a firm but yielding resistance (which is variable by adjustment of the stem 281) to movement of the latches towards the right during the final cycle of the machine and therefore causes the cooperating clutch member 227 to be urged firmly against the stationary braking face 229 without however being jammed too severely against it.

A relatively strong and adjustable spring 283 bearing at its lower end upon the upper end of the valve 265 in the oil chamber 263 and bearing at its upper end against a vertically adjustable stud 285 tends normally to maintain the valve tightly upon its seating 267 and therefore to prevent oil from being forced out of the cylinder 271 through the duct 269 and into the chamber 263 by the descent of the plunger 273 except when the plunger is moved downwardly at a relatively high speed (as occurs in the manner hereinafter described as soon as the trip lever 237 engages the shoulder 261 on the forward latch 245 in stopping from high speed). The precise condition under which the valve 265 will rise from the seating is of course determined by the strength of the spring 283 acting on the valve which is adjustable by means of the stud 285. In order however to allow oil to flow freely from the chamber 263 into the cylinder 271 as the plunger 273 is raised by means of a spring 287 located between it and the bottom of the cylinder 271 on the restarting of the machine into operation in the manner hereinafter described, a passage 289 is bored upwardly in the valve 265 from its lower end and communicates by means of lateral openings 291 at its upper end with the interior of the chamber 263. A light spring 293, seated upon an inturned rim around the lower end of the valve bears at its upper end against a ball 295 and urges it upwardly against a narrowed neck in the passage 289. The ball 295 and the passage 289 constitute a one-way valve through which oil may readily flow downwardly under the suction created by the upward movement of the plunger 273 but which prevents upward flow of oil through the valve from the cylinder 271 to the chamber 263.

From what has just been said it will be appreciated that the separation of the cooperating clutch member 227 from the pulley 13 and the pressure with which it is forced against the stationary braking face 229 are controlled by the cooperation of the trip levers 237, 239 with the

latches 245, 247 and that the lateral displacement of the latches under the pressure exerted on them by the trip levers is resisted by the dashpot device. It will also be gathered that the engagement between the trip lever 237 and the latch 245 which takes place at the commencement of the stopping from high speed will tend to force the plunger 273 rapidly downwards along its cylinder but that, owing to the bleed valve 279 being of relatively small diameter, the dashpot will offer a greater resistance to quick downward movement of the plunger than it will offer to comparatively slow movement of the plunger and therefore that at the instant when the clutch member 227 is first forced against the braking face 229 in stopping from high speed, the pressure exerted between these two members will be greater than at any other period in the stopping of the machine parts. It will moreover be appreciated that as the speed of the moving parts falls, the speed with which the plunger 273 is forced downwardly along its cylinder will also fall and therefore the resistance offered to its movement by the dashpot will likewise fall, thus giving the result that the braking pressure exerted on the moving parts will gradually decrease in accordance with the decreasing speed of movement of the parts.

In the machine now being described means is provided to allow the cooperating clutch member 227 to be held pressed against the stationary braking face 229 for a longer portion of the final cycle of the machine when stopping from high speed than when stopping from low speed to provide ample time for the parts to be brought to rest relatively gradually.

This is effected by causing the latches 245, 247 to move towards the left of the machine (i. e. towards the trip levers) through a chosen distance when the machine is started into operation at high speed so that the trip lever 237 will engage the latch 245 at an early time in the final cycle of the machine and by causing the latches to move through a lesser distance in this direction (so that the trip lever 239 will engage the latch 247 at a later time in the final machine cycle), when the machine is started into operation at low speed.

The means for so moving the latches toward the left comprises the spring 287 aforementioned which lies beneath the plunger 273 of the dashpot, this spring acting, when the treadle 17 is depressed to start the machine into operation, to rock the bell crank lever 251, 255 in a clockwise direction looked at from the front and thus to move the latches in the desired direction. In order to limit the extent of movement of the latches towards the left when the machine is started into operation at low speed, there is pivoted on the pin 249 on which the latches are mounted, a finger 297 which lies behind and close against the latch 247, this finger being normally upheld against the lower face of a forwardly extending stop plate 299 secured to the machine frame. This finger has an upstanding shoulder 301 (see Figure 4) which, in the stopped position of the machine, lies a short distance away from the right hand face of the stop plate 299. When the treadle is depressed only far enough to cause the machine to run at low speed the arrangement hereinafter described which then draws the latch 247 downwardly away from the trip lever 239 does not disturb the heightwise position of the finger 297 and therefore when the latches are moved to-

wards the left by the spring 287, the shoulder 301 on the finger abuts against the right hand face of the stop plate and therefore limits the movement of the latches towards the left. When 5 however the treadle is depressed far enough to cause the machine to run at high speed both latches 245, 247 are drawn downwardly and the finger 297 is also drawn downwardly away from the stop plate 299 so that the spring 287 can 10 move the latches (and the finger) still further towards the left until their movement is arrested by contact of the arm 255 of the bell crank lever 251, 255 15 with a fixed stop 303 on the machine frame.

15 The arrangement above referred to for withdrawing the latches downwardly away from the trip levers when the treadle 17 is depressed to start the machine into operation comprises a rising and falling plate 305 held normally in a 20 vertical position against a stop 306 (Figure 3) contacting with its right hand face by a spring 308. This plate has an opening 307 cut in it through which the left hand ends of the latches 245, 247 and of the finger 297 extend. The 25 plate 305 is secured to the upper end of a stem 309 which is pivoted at its lower end on a forwardly and rearwardly extending pin 311 carried by an arm 313 which is secured on a rocking shaft 315 which also carries a second arm 317 which is connected by a rod 319 to the rearward end of the treadle 17, a spring 321 (Figure 1) connected at its upper end to the rod and at its lower end to a fixed pin tending to raise the plate 305 to the position shown best in 30 the Figure 5. The opening 307 in the plate 305 is substantially rectangular in shape but has a downwardly projecting tongue 323 located on its upper edge, the tongue being arranged directly over the latch 247. When the treadle 17 35 is depressed only far enough to start the machine into operation at low speed the plate 305 will be drawn downwardly far enough only to cause the tongue 323 to urge the latch 247 out of engagement with the trip lever 239, leaving the positions of the latch 245 and the finger 297 40 undisturbed. As will hereinafter become clear the latch 247 alone of the two latches is in engagement with its trip lever when the machine is stopped and therefore withdrawal of this latch from the trip lever will allow the springs 243 to 45 urge the cooperating clutch member 227 into engagement with the pulley 13. When this latch has been withdrawn from its trip lever the spring 267 in the dashpot will cause the latches 50 to move towards the left until they are arrested by contact of the shoulder 301 on the finger 297 with the stop plate 299.

When the treadle is depressed far enough to cause the machine to run at high speed, the portions 55 of the upper edge of the opening 307 in the plate 305 on opposite sides of the tongue 323 will be brought down sufficiently far to abut against the latch 245 and the finger 297 and to move them respectively away from the trip lever 237 60 and the stop plate 299, the latch 247 being of course also depressed by the tongue 323 at this time. When this has taken place the latches will be moved towards the left until they are arrested by the stop 303.

65 When the treadle has been depressed only far enough to start the machine into operation at low speed (and has therefore pulled downwardly only the latch 247) and is thereafter allowed to rise to bring the machine to rest, the latch 247 70 is allowed to rise by the rising of the tongue 323

and its shoulder 259 will be engaged by the trip lever 239 when the latter next springs towards the right. When this occurs the trip lever will immediately commence to move the latches towards the right against the action of the dashpot and the braking effort will immediately become operative to reduce the momentum of the moving parts, the movement of the latches continuing until a face 325 on the right hand side of the arm 251 of the bell crank lever 251, 255 10 strikes against a fixed part of the machine frame and therefore arrests the further movement of the latches. The arresting of the movement of the latches causes the cooperating clutch member 227 to be urged somewhat more firmly, for 15 a very short period, against the stationary braking face 229 to ensure that the parts will be brought to rest with the needle and awl in the desired positions out of the work.

When however the treadle has been depressed 20 far enough to start the machine into operation at high speed (and has therefore pulled downwardly both the latches 245, 247) and is thereafter allowed to rise to bring the machine to rest it is desirable to avoid wearing away of the shoulder 25 25 261 of the latch 245 by the lower end of the trip lever 237 due to premature engagement of the latch with the trip lever and for this purpose means is provided for ensuring that the latch 245 will be allowed to engage the trip lever only when 30 the lower end of the latter occupies a position to the left of the shoulder. The said means comprises a rearwardly extending spring pressed plunger 327 arranged in a fixed part of the machine, the rear end of the plunger having a nose 35 arranged, when the latch 245 has been drawn downwardly by the treadle in the starting of the machine into high speed, to project over the forward side of this latch. When the treadle is later released the latch is allowed to rise until it is arrested by this plunger which occupies such a heightwise position that the latch will be maintained temporarily by it out of contact with the trip lever 237. The rearward latch 247 has secured to its underside a forwardly projecting lug 40 45 329 (Figures 2 and 3) which is arranged, when the latch 245 is engaged by the plunger 327, to contact with the underside of the latch 245 and thus prevent the latch 247 from rising into contact with the lower end of the trip lever 239 until the latch 245 is released from the plunger, thus avoiding the unnecessary wear which would take place on the upper face of the latch 247 if it were allowed to abut against the trip lever 239 50 immediately the treadle is released.

55 In order to cause the plunger 327 to release the latches to allow them to ride into engagement with their trip levers, the plunger is provided at the right hand side of its rear end with a bevelled face 331 and the plate 305, which is provided with a bevelled edge 333 extending upwardly along its forward edge, is arranged to be rocked to the left about the pivot 311 at the appropriate time to urge the plunger 327 forwardly to release the latches. In order to rock the plate for this purpose, the lever 237 is provided on its left hand face with a thickened portion 335 which, when the plate occupies its highest position, is arranged to strike against the plate as the lower end of the trip lever 237 reaches the left hand end portion 60 65 of its travel and thus rock the plate towards the left, the plate being returned to its original position as the trip lever swings back by the spring aforementioned which is coupled to it.

70 The driving mechanism and the stop motion of 75

the machine operate as follows: Assuming the treadle 17 not to be depressed the pulley 13 on the main shaft will be driven idly at low speed by the pulley member 195 through the epicyclic gearing on the countershaft. When the treadle is depressed only far enough to cause the machine to operate at low speed (an indication being given to the operator when the treadle has reached this position by means of a spring 337 Figure 1 encircling the rod 319 abutting against a relatively fixed but adjustable stop screw 339 through which the rod passes) the latch 247 is drawn downwardly away from contact with the trip lever 239 to disengage its shoulder from the trip lever (the shoulder on the latch 245 being spaced away to the right in an inoperative position relatively to the trip lever 237 when the machine is in stopped position and it being unnecessary to disturb the position of this latch at this time) and the springs 243 in the cooperating clutch member 227 will therefore act immediately to cause the cooperating clutch member to become clutched to the pulley 13 to drive the machine at low speed. Sufficient clearance is provided in the two speed driving device between the members 205 and 199 to ensure that the partial depression of the treadle will not cause the member 195 to become clutched to the member 205.

Immediately the latch 247 is drawn downwardly away from the trip lever 239 the spring 227 in the dashpot will cause the latches to move smartly towards the left until the shoulder 301 on the finger 297 abuts against the stop plate 299, this plate however being so positioned that it will arrest the movement of the latches before the shoulder 261 on the latch 245 reaches a position such that the lower end of the trip lever 237 can strike against it as this lever rocks to and fro. The parts remain in this position until the treadle is released to cause the machine to be brought to rest and when this is done the latch 247 is immediately allowed to rise into contact with the lower end of the trip lever 239 which latter as it next swings towards the right strikes against the shoulder 259 on the latch and therefore commences to move the latches back again towards the right. The backward movement of the latches is resisted by the dashpot which therefore causes the cooperating clutch member 227 to become unclutched from the pulley 13 and to be pressed firmly against the stationary braking face 229 whereupon the speed of the moving parts immediately begins to fall. As the speed falls, the plunger 273 in the dashpot moves more slowly down its cylinder and thus allows the bleed valve 279 to become gradually more effective to reduce the oil pressure below the plunger and thus to bring about a gradual and even decrease in the braking effort applied to the moving parts. When the parts have almost reached the positions in which it is desired that they shall be stopped the face 325 on the arm 251 abuts against its cooperating stationary face and thus brings about a momentary increase in the braking pressure which ensures that the parts will in fact be brought to rest in the desired positions. By arranging for the trip lever 239 and the latch 247 to cooperate in this manner, the braking effort may be applied to the moving parts throughout about the last one hundred and fifty degrees of the final machine cycle.

If, while the machine is operating at low speed or while it is stopped, the treadle is fully depressed to cause the machine to operate at its high speed, the pulley member 195 on the

countershaft will become clutched to the member 205 to be driven thereby at high speed and if the latch 247 has not already been pulled downwardly by depression of the treadle to start the machine into operation at low speed, both the latches 245 and 247 will be drawn downwardly out of engagement with the trip levers and the finger 297 will also be drawn downwardly out of engagement with the stop plate 299. The spring 227 in the dashpot will immediately cause the latches to move towards the left a distance further than they were moved by the spring when the machine was started into operation at low speed, until their movement is arrested by the stop 303. When this occurs, the shoulder 261 on the latch 245 will have moved so far towards the left as to occupy the same position, considered forwardly and rearwardly of the machine, as the shoulder 259 on the latch 247 occupies during the low speed operation of the machine, this latter shoulder having, of course, moved still further towards the left.

The latches remain in their downward position until the treadle is released to cause the machine to be brought to rest from high speed. When the treadle is released the latches 245, 247 rise until they are arrested by the nose on the plunger 327, the finger 297 also rising until that portion of its upper face to the right of the shoulder 301 abuts against the lower edge of the stop plate 299, the plate 305 continuing to its highest position (which is determined by contact of the forward portion of the treadle with a fixed but adjustable stop screw 341, Figures 35 1 and 2).

As previously stated, the lower ends of the two trip levers 237, 239 move continually to and fro during the running of the machine, the lower end of the trip lever 239 moving to the left as the lower end of the trip lever 237 moves towards the right and vice versa.

When, after the plate 305 has risen to its highest position, the lower end of the trip lever 237 next swings towards the left, the thickened portion 335 on it will strike against the plate 305 and swing it towards the left to cause the plunger 327 to be cammed forwardly to release the latches and allow them to rise into contact with the lower end of their respective trip levers. When the latch 245 thus engages the lower end of the trip lever 231, the shoulder 261 on it will rise almost into contact with the right hand face of the lower end of the trip lever (which latter will at this time be at substantially the left hand limit of its stroke) and therefore when the lower end of this trip lever next swings towards the right, its engagement with the shoulder will cause the latches to commence also to move in this direction. Since the machine will at this time be running at its high speed, the trip lever will tend to urge the latches rapidly towards the right and thus urge the plunger 273 in the dashpot rapidly down its cylinder. As however, the bleed valve 279 in the plunger is of but a small area, the oil beneath the plunger will offer a very firm resistance to downward movement of the plunger and will thus cause the cooperating clutch member 227 to be moved firmly into contact with the stationary braking face 229. In order, however, that the braking effort thus exerted on the moving parts shall not be so severe as to result in shock to the machine, the spring 283 above the central valve 265 in the dashpot will have been so adjusted that the valve can be 75

forced upwardly temporarily away from its seating under the pressure exerted on the oil by the downward movement of the plunger, and thus relieve to a desired degree the force with 5 which the cooperating clutch member is initially forced against the stationary braking face. As will be understood, this valve regains its seating when the pressure below the plunger diminishes to an extent which allows the valve to be forced 10 downwardly by the spring 283.

As the trip lever 237 continues to move the latches towards the right, the braking effort will act to decrease progressively the momentum of the moving parts and, therefore, the speed with 15 which the latches are urged towards the right and the speed with which the plunger 273 is forced downwardly along its cylinder. The more slowly the plunger descends along its cylinder, the more effective will the bleed valve 279 become in relieving the pressure on the oil beneath the plunger and, therefore, the smaller will become the resistance of the downward movement of the plunger, thus bringing about the result that a decrease in the braking effort accompanies 20 the decrease in momentum.

The lower ends of the two trip levers move, as will be understood, through equal distances as they move to and fro and the distance which the shoulders 259, 261 are spaced apart on their 30 latches from left to right of the machine is equal to the stroke of the lower ends of the trip levers, the shoulder 259 being further to the left of the machine than the shoulder 261. Therefore, when the trip lever 237 has moved the latches as far 35 towards the right as it can, the shoulder 259 on the latch 247 will have been brought into line with the right hand face of the lower end of the trip lever 239, the latch then being caused by its spring 257 to rise until the portion to the left 40 of the shoulder rests against the end of the trip lever. The trip lever 237 then commences to retire to the left away from engagement with the shoulder 261 on the latch 245 and the trip lever 239 commences to move towards the right 45 to continue the movement of the latches in this direction by engagement with the shoulder 259. From that time until the face 325 abuts against its cooperating stationary face to arrest the movement of the latches and ensure that the 50 parts are actually brought to rest in the positions desired, the trip lever 239 and the latch 247 continue to maintain the co-operating clutch member pressed against the stationary braking face 229 under a progressively decreasing pressure through the action of the dashpot in the 55 manner previously described with reference to the stopping of the machine from low speed.

Conveniently, the spring 283 above the valve 265 in the dashpot will previously have been so 60 adjusted to control the resistance offered to descent of the plunger 273 that immediately the latter is urged down its cylinder at the commencement of the stopping from high speed to cause the trip lever 239 to engage the shoulder 259 on the latch 247, the speed of the parts will 65 have been reduced substantially to the speed at which the parts will be moving when that lever engages that shoulder in the stopping of the machine from low speed in the manner hereinbefore described.

It will therefore be seen that in the stopping 70 of the machine from high speed the two trip levers operate to impart to the latches a movement towards the right which is substantially 75 equal in extent to twice that which they receive,

under the action of the trip lever 239 alone, in the stopping of the machine from its low speed and that, therefore, the braking effect on the machine parts will continue during a portion of the final machine cycle when stopping from high 5 speed substantially equal to twice that during which the braking effort is effective during the final cycle when stopping from low speed, i. e. the braking effort is effective throughout about the last three hundred degrees of rotation of the 10 final machine cycle.

In sewing around the end corners of rectangular cases or the like it is often desired to sew a single stitch actually in the corner while the machine is in operation at low speed and the 15 stopping mechanism above described is found particularly suitable for allowing the machine to insert single stitches in the work since it operates to bring the machine to rest in a very smooth and shock-free manner with the parts in precisely the positions desired.

Moreover, the pressure exerted by the trip lever 239 on the shoulder of the latch 247 as the machine actually comes to rest will be so light as to require but a small effort to pull this 25 latch away from the trip lever in the starting of the machine, this being a matter of considerable advantage in a machine, such as is described above, which is often required to insert single stitches in successive corners of the work 30 and which, therefore, may require to be tripped a number of times when sewing round a single case or the like.

Such a stopping mechanism as is just above described may be found of advantage not only 35 in machines which are particularly arranged to sew together parts of suit cases or the like, but also in other machines which are arranged to run at high speed such, for example, as boot and shoe outsole sewing machines of the type 40 disclosed in Patent No. 2,056,670 or of other similar types.

The sewing machine disclosed in this application, as originally filed, forms the subject-matter of divisional application Serial No. 200,635 filed 45 April 7, 1938.

The nature and scope of the invention having been indicated, and a machine embodying the several features of the invention having been specifically described, what is claimed is: 50

1. A driving and stopping mechanism having, in combination, a driven shaft, a main driving pulley for causing the driven shaft to be rotated, a brake for bringing the driven shaft to rest, and mechanism actuated by the driven shaft when 55 set into operation to apply the brake with a progressively decreasing effort.

2. A driving and stopping mechanism having, in combination, a driven shaft, a main driving pulley for causing the driven shaft to be rotated, 60 a brake for bringing the driven shaft to rest, and mechanism actuated when set into operation to apply the brake with an effort decreasing progressively with the speed of the driven shaft.

3. A driving and stopping mechanism having, in combination, a driven shaft, a main driving pulley for causing the driven shaft to be rotated, a brake for bringing the driven shaft to rest, mechanism actuated by the driven shaft when 70 set into operation to apply the brake with a progressively decreasing effort, and means for finally bringing the driven shaft to rest at a predetermined position.

4. A driving and stopping mechanism having, 75

- in combination, a driven shaft, a main driving pulley for causing the driven shaft to be rotated, a brake for bringing the driven shaft to rest, a cam on the driven shaft, a lever operated by the cam, connections for causing the cam lever to actuate the brake, and means for progressively decreasing the effectiveness of the connections in applying the brake as the speed of the driven shaft is reduced.
5. A driving and stopping mechanism having, in combination, a driven shaft, a driving pulley on the shaft, a stationary brake member, a clutch member on the shaft arranged to engage either the driving pulley or the brake member, a cam connected to the clutch member, a lever oscillated by the cam, a dashpot, a piston in the dashpot, means connected to the piston for restraining the lever to cause the clutch member to be disengaged from the driving pulley and engaged with the brake member, and means for progressively decreasing the restraining effort of the restraining means as the speed of the driven shaft is reduced.
10. A driving and stopping mechanism having, in combination, a driven shaft, a driving pulley on the shaft, a stationary brake member, a clutch member on the shaft arranged to engage either the driving pulley or the brake member, a cam connected to the clutch member, a lever oscillated by the cam, means for restraining the lever to cause the clutch member to be disengaged from the driving pulley and engaged with the brake member, and means for progressively decreasing the restraining effort of the restraining means as the speed of the driven shaft is reduced.
15. A driving and stopping mechanism having, in combination, a driven shaft, a driving pulley on the shaft, a stationary brake member, a clutch member on the shaft arranged to engage either the driving pulley or the brake member, a cam connected to the clutch member, a lever oscillated by the cam, a dashpot, and means connected to the dashpot for restraining the lever to cause the clutch member to be disengaged from the driving pulley and forced against the brake member as the speed of the driven shaft is reduced.
20. A driving and stopping mechanism having, in combination, a driven shaft, a main driving clutch for causing the driven shaft to be rotated, a brake for bringing the driven shaft to rest, means actuated when the shaft reaches a predetermined position to render the main clutch member inoperative and to apply the brake when the shaft is rotated at one speed, and means actuated to apply the brake at another predetermined position of the shaft when the shaft is rotated at a different speed.
25. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a dashpot, a piston in the dashpot, means connected to the piston for restraining the lever to cause the clutch member to be disengaged from the driving pulley and forced against the brake member as the speed of the driven shaft is reduced.
30. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a dashpot, and means connected to the dashpot for restraining the lever to cause the clutch member to be disengaged from the driving pulley and forced against the brake member with an effort decreasing as the speed of the driven shaft is reduced.
35. A driving and stopping mechanism having, in combination, a driven shaft, a main driving clutch for causing the driven shaft to be rotated, a brake for bringing the driven shaft to rest, means actuated when the shaft reaches a predetermined position to render the main clutch member inoperative and to apply the brake when the shaft is rotated at one speed, and means actuated to apply the brake at another predetermined position of the shaft when the shaft is rotated at a different speed.
40. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever to cause the clutch member to be disengaged from the driving pulley, and engaged with the brake member, a carrier for the latch, and a dashpot for resisting movement of the carrier.
45. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever to cause the clutch member to be disengaged from the driving pulley, and engaged with the brake member, a carrier for the latch, a dashpot for resisting movement of the carrier, a treadle for releasing the lever from the latch, and connections actuated by the treadle to change the movement resisting effect of the dashpot.
50. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever to cause the clutch member to be disengaged from the driving pulley, and engaged with the brake member, a carrier for the latch, a dashpot for resisting movement of the carrier, a treadle for releasing the lever from the latch, and connections actuated by the treadle to change the movement resisting effect of the dashpot.
55. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, latches for restraining the movements of the respective levers to cause the clutch member to be disengaged from the driving pulley and engaged with the brake member, a

movable carrier for the latches, a dashpot for resisting movement of the carrier, a treadle, mechanism actuated when the treadle is depressed to rotate the driving pulley at different speeds, and latch actuating connections controlled by the treadle when the driving pulley is rotated at low speed to cause the carrier after the treadle is released to be moved by the oscillating levers a predetermined distance in stopping the driven shaft, 5 and when said mechanism rotates the driving pulley at a higher speed, to cause the carrier to be moved by the oscillating levers a greater distance in stopping the driven shaft.

16. A driving and stopping mechanism having, in combination, a driven shaft, a main driving pulley on the shaft, a stationary brake member, a clutch member on the shaft arranged to engage either the driving pulley or the brake member, a cam connected to the clutch member, levers oscillated alternately by the cam, latches for restraining the movements of the respective levers to cause the clutch member to be disengaged from the driving pulley and engaged with the brake member, a carrier for the latches, a dashpot for resisting movement of the carrier, a treadle, mechanism actuated when the treadle is depressed to rotate the driving pulley at different speeds, and latch actuated connections controlled by the treadle when the driving pulley is rotated at low speed to cause the carrier after the treadle is released to be moved by one only of the oscillating levers in stopping the driven shaft, and when the driving pulley is rotated at higher speed to cause the carrier to be moved successively by said levers in stopping the driven shaft.

17. A driving and stopping mechanism having, in combination, a driven shaft, a main driving pulley on the shaft, a stationary brake member, a clutch member on the shaft arranged to engage either the driving pulley or the brake member, a cam connected to the clutch member, levers oscillated alternately by the cam, latches for restraining the movements of the respective levers to cause the clutch member to be disengaged from the driving pulley and engaged with the brake member, a carrier for the latches, a dashpot for resisting movement of the carrier, a stop plate, a stop latch on the carrier for engaging the stop plate to hold the carrier in predetermined position, a treadle, mechanism actuated when the treadle is depressed to rotate the driving pulley at different speeds, and latch actuating connections controlled by the treadle when the driving pulley is rotated at low speed to cause the carrier, after the treadle is released, to be moved by one only of said levers in stopping the driven shaft and, when the driving pulley is rotated at higher speed, to release the stop latch from the stop plate and cause the carrier to be moved successively by the oscillating levers in stopping the driven shaft.

18. A driving and stopping mechanism having, in combination, a driven shaft, a main driving pulley on the shaft, a stationary brake member, a clutch member on the shaft arranged to engage either the driving pulley or the brake member, a cam connected to the clutch member, levers oscillated by the cam, latches for restraining the movements of the respective levers to cause the clutch member to be disengaged from the driving pulley and engaged with the brake member, a movable carrier for the latches, a dashpot for resisting movement of the carrier, a treadle, mechanism actuated when the treadle is depressed to rotate the driving pulley at different

speeds, and connections controlled by the treadle when the driving pulley is rotated at low speed to locate the carrier in a position in which it will be moved after the treadle is released by one only of the levers in stopping the driven shaft and, when the driving pulley is rotated at higher speed, to locate the carrier at a position in which it will be moved successively by the oscillating levers in stopping the driven shaft.

19. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever during its movement in one direction to cause the clutch member to be disengaged from the driving pulley and engaged with the brake member, a treadle for releasing the lever from the latch, and means for preventing the latch from engaging the lever during movement of the lever in the other direction.

20. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever during its movement in one direction to cause the clutch member to be disengaged from the driving pulley and engaged with the brake member, a treadle for actuating the latch to permit the latch to engage or disengage the lever, means engaging the latch to prevent the latch from engaging the lever prematurely.

21. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever to cause the clutch member to be disengaged from the driving pulley, and engaged with the brake member, a carrier for the latch, a dashpot for resisting movement of the carrier, and means for limiting the resistance with which the dashpot acts.

22. A driving and stopping mechanism having, in combination, a driven shaft, a main driving pulley on the shaft, a stationary brake member, a clutch member on the shaft arranged to engage either the driving pulley or the brake member, a cam connected to the clutch member, a lever oscillated by the cam, a latch for restraining the movement of the lever to cause the clutch member to be disengaged from the driving pulley, and engaged with the brake member, a carrier for the latch, a dashpot for resisting movement of the carrier, and a spring loaded valve connected with the dashpot for limiting the resistance with which the dashpot acts.

23. A driving and stopping mechanism having, in combination, a driven shaft, a pulley on the shaft, a driving mechanism for rotating the pulley at high or low speeds, a ratchet wheel in said mechanism, a pawl engaging said ratchet wheel to permit the ratchet wheel to rotate in one direction relatively to the pawl when the pulley is rotated at high speed and to hold the ratchet wheel when the pulley is rotated at low speed, and friction means for actuating the pawl

out of engagement with the ratchet wheel when the wheel is rotated relatively to said pawl.

24. A driving and stopping mechanism having, in combination, a driven shaft, a constantly rotating countershaft, a driving pulley on the counter-shaft for rotating the driven shaft, pinions on the driving pulley, a gear or counter-shaft engaging the pinions, an internal gear surrounding the pinions, a ratchet wheel on the internal gear, 10 a spring pressed pawl engaging the ratchet wheel to hold the internal gear from rotation in a direction opposite from that of the countershaft, a clutch member for driving the internal gear in the same direction as the counter-shaft, and a friction producing element on the pawl engaging the internal gear to throw the pawl out of engagement with the ratchet wheel when the internal gear rotates in the same direction with the counter-shaft.
25. A driving and stopping mechanism having, in combination, a driven shaft, a pulley on the shaft, a driving mechanism for rotating the pulley at high or low speeds, a spring actuated treadle for controlling the speed at which the driving mechanism rotates the pulley, yielding means connected to the treadle for indicating to the oper-

ator by a marked increase in pressure required to operate the treadle whenever the treadle is moved from low speed to high speed position, and means for regulating the position of the treadle at which the yielding means becomes effective. 5

26. A driving and stopping mechanism having, in combination, a driven shaft, a main driving pulley on the shaft, a stationary brake member, a clutch member on the shaft arranged to engage either the driving pulley or the brake member, a cam connected to the clutch member, levers oscillated alternately by the cam, latches having shoulders for restraining the movements of the respective levers to cause the clutch member to be disengaged from the driving pulley and engaged with the brake member, a carrier on which the latches are mounted with their shoulders spaced from each other in the direction of lever oscillation a distance substantially equal 10 to the stroke of said levers, means for resisting movement of the carrier, and means for suitably positioning the carrier to cause one or both of the latches to be engaged by the levers. 15

JOSEPH GOULDBOURN.
